WITNESS: *J. W. Eley*

UNITED STATES PATENT OFFICE.

JAMES EDWARD HODGSON, OF NEW YORK, N. Y.

EMBROIDERY-MACHINE.

1,395,961.

Specification of Letters Patent.

Patented Nov. 1, 1921.

Application filed December 4, 1920. Serial No. 428,316.

To all whom it may concern:

Be it known that I, JAMES EDWARD HODGSON, a citizen of the United States, residing at New York city, in the county of New 5 York and State of New York, have invented new and useful Improvements in Embroidery-Machines, of which the following is a specification.

This invention relates to improvements in 10 embroidery machines, and one of the principal objects is to produce a device of this nature which shall be simple in construction, cheap to manufacture, and highly efficient for the purpose for which it is designed.

15 Another object is to provide a device of this nature with an adjustable handle for regulating the length of stitch.

Another object is to so construct the device 20 that it will automatically "walk" along from one punching position to the next.

With these and other objects in view which will become apparent as the specification proceeds, the invention consists of certain novel construction and combination and arrangement of parts, the essential features of which are hereinafter fully described and specifically pointed out in the claims and which are shown in the accompanying drawing, in which:

25 Figure 1 is a perspective view of my improved embroidery machine.

Fig. 2 is a side view of the same.

Fig. 3 is a vertical sectional view from front to rear of the device.

30 Like characters of reference refer to like parts in all views.

This invention contemplates the producing of a simple embroidery machine for doing "punch work" or tufting wherein the tubular 40 needle is slidably mounted in an upward extension of the foot member and is provided near its upper end with a handle for operating it which handle may be adjusted longitudinally of the needle for varying the 45 length of stroke of the needle.

Referring to the drawings more in detail, 10 represents a tubular tufting needle which is bent at an angle at 11 and is provided with an eye 12 in its point as is usual.

50 A length of wire is bent to form a foot 13, a rearwardly extending offset portion 14 and upwardly extending arms 15 which converge at 16 so as to lie on opposite sides of the needle 10 and are secured together by a thin 55 strip of metal 17 which is soldered to the

arms 15 and forms a guide way for the vertical movement of the needle 10. A second guide member 18 is soldered to the needle 10 and embraces the arms 15 below their convergence and above the foot 13, thus serving 60 the double purpose of stop for upward movement of the needle and guide for directing the needle and preventing relative turning of the needle and foot.

A handle 19 is secured to the upper end of 65 the needle by the set screw 20 and serves the double purpose of permitting an adjustment of the length of throw of the needle, and of an operating handle.

The offset portion 14 and the angular bend 70 in the needle at 11 co-act with the material in such manner as to effect movement of said foot along the material upon the reciprocation of the device.

While I have described what I deem to be 75 the most desirable embodiment of my invention, it is obvious that many of the details may be varied without in any way departing from the spirit of my invention, and I therefore do not limit myself to the exact 80 details of construction herein set forth nor to anything less than the whole of my invention limited only by the appended claims.

What is claimed as new is:—

1. In a device of the class described, the 85 combination of a tubular needle having an angularly bent lower portion, a length of wire bent to form a foot and an offset portion and a pair of legs lying parallel with said needle, a guide member securing the legs 90 of said wire together and forming a guideway for said needle, and a guide member secured to said needle between the first guide member and said foot and embracing said legs.

2. In a device of the class described, the 95 combination of the tubular needle having an angularly bent lower portion, a length of wire bent to form a foot and an offset portion and a pair of legs lying parallel with said needle, a guide member securing the 100 legs of said wire together and forming a guideway for said needle, a guide member secured to said needle between the first guide member and said foot and embracing said legs, and an adjustable finger piece on said 105 needle.

In testimony whereof I have affixed my signature.

JAMES EDWARD HODGSON.
